UNITED STATES PATENT OFFICE.

GEORGE B. LUDY, OF CEDAR RAPIDS, IOWA.

DESIGN FOR A SPOON.

No. 38,678.

Specification for Design.

Patented July 16, 1907.

Application filed June 3, 1907. Serial No. 377,117. Term of patent 7 years.

To all whom it may concern:

Be it known that I, GEORGE B. LUDY, a citizen of the United States, residing at Cedar Rapids, in the county of Linn and State of Iowa, have invented a new, original, and ornamental Design for Spoons, of which the following is a specification, reference being had to the accompanying drawing, forming a part thereof.

The figure is a plan view of a spoon, showing my new design.

I claim:

The ornamental design for a spoon, as shown.

GEORGE B. LUDY.
